Attorney

WITNESS:

Chas. L. Griesbauer

UNITED STATES PATENT OFFICE.

LEROY SAXON WORSLEY, OF TAMPA, FLORIDA.

STEAMER.

Application filed January 23, 1923. Serial No. 614,481.

To all whom it may concern:

Be it known that I, LEROY SAXON WORSLEY, a citizen of the United States, residing at Tampa, in the county of Hillsborough 5 and State of Florida, have invented certain new and useful Improvements in Steamers, of which the following is a specification, reference being had therein to the accompanying drawing.

10 This invention relates to a device for producing steam in comparatively small quantities and at comparatively low pressure, for steaming batteries, steaming clothes, for use by dressmakers and others 15 in the application of moisture to goods upon which work is being performed, and for other purposes.

It is an object of the invention to provide a device of that kind that is simple in construction, easy and economical to produce, requires no safety-valve or pressure-gage, cannot explode, and that can have heat applied thereto in any convenient manner as by being placed over a gas or liquid-fuel 25 burner or on a stove of the domestic type burning gas or liquid or solid fuel.

When considered in connection with the description herein, the characteristics of the invention will be apparent from the accompanying drawing, forming part hereof, 30 wherein an embodiment of the invention is disclosed, for purposes of illustration.

Like reference-characters refer to corresponding parts in the views of the drawing, of which—

Fig. 1 is a top view; and

Fig. 2 is a vertical longitudinal section.

Having more particular reference to the drawing, 3 designates a casing, which preferably is flat on the bottom so that it can be placed conveniently on any available heater, and which in the type disclosed by the drawing is of rectangular shape.

The top wall of the casing is formed near 45 one end with an opening 4, which in the embodiment disclosed is of circular form, and the opening is surrounded by a depending inwardly-inclined flange 5.

The interior of the casing is divided into 50 a filling-chamber A and a steam-chamber B by a partition 6. The partition extends between, and has a fluid-tight joint with, the side walls of the casing and at its top with the upper wall. It extends in downwardly-inclined disposition from the upper

wall under the major portion of the filling-chamber and under the opening 4 and nearly to the bottom of the casing.

The arrangement of the partition is such that an elongated opening 7 extends from side to side of the casing and between the bottom thereof and the lower edge of the partition, this opening constituting a passage that affords in the bottom of the steamer communication between the two 65 chambers.

A nipple 8 leads from an opening in the top wall of the casing above the steam-chamber, for the purpose of permitting discharge of steam from that chamber. The 70 nipple, which constitutes the steam-outlet, has a control-valve 9, and it is formed at its end in such manner that a flexible or other pipe 10 may be connected thereto for the purpose of conveying steam to the place it 75 is desired to be used.

Water is introduced into the casing by pouring through the opening 4 into the filling-chamber, whence it passes through the opening 7 into the steam-chamber until the 80 level in both chambers is the same, it being assumed that the valve 9 is open at that time. The amount of water in the casing can be ascertained at any time by observing the level in the filling-chamber.

When heat is applied to the bottom of the casing, water vapor or steam is evolved in the steam chamber, whence it passes through the outlet controlled by the valve 9.

If, during operation of the device, the 90 valve is left closed long enough to permit accumulation of an excess of evolved vapor in the steam-chamber, the pressure of vapor in that chamber simply will force water in the bottom thereof through the opening 9 95 until water reaches the level of the bottom edge of the partition, and then excess vapor will escape through that opening and into the water in the filling-chamber. Steam not condensed in that water will escape to the 100 surface thereof. It thus will be understood that there is no danger of the steamer exploding, as it is not possible for vapor in the steam-chamber to reach pressure sufficient to cause that result.

In view of the fact that the lower edge 105 of the partition is above the bottom of the casing, enough water will remain in the steam-chamber to prevent injury by heat to the bottom thereof as long as water remains 110

in the filling-chamber, and the operator always can observe the quantity of water in the latter chamber through the opening 4.

The only disadvantageous result that may occur from excess pressure in the steam-chamber is when there is too much water in the steamer and it is caused to overflow through the opening 4. Introduction of too much water may be avoided by keeping the valve 9 closed while pouring water through the opening 4. Under that condition water will pass into the steam-chamber only until a level at or slightly above the lower edge of the partition is reached, then it will accumulate in the filling-chamber, and addition of water should be stopped before that chamber is entirely filled. If that precaution is observed, the steamer at no time will contain enough water to cause overflow through the opening 4, even when water from the steam-chamber is caused by steam pressure to flow back into the filling-chamber.

One purpose of the flange 5 is to permit accumulation, therearound in the upper portion of the filling-chamber, of steam that may arise from the surface of the water in that chamber. Although all of the steam that may be evolved in the filling-chamber may not thus collect and some of it may pass out of the opening 4, a considerable portion thereof will have a tendency to accumulate around the flange and condense, and the condensation will drip from the lower edge of the flange.

Having thus described my invention, what I claim as new, and desire to secure by Letters Patent, is—

1. A steamer comprising a casing having a top wall and being arranged to have heat applied to the bottom thereof, and a partition dividing the interior of said casing into a filling-chamber and a steam-chamber and extending in downwardly-inclined disposition from the top wall of said casing toward the bottom and under said filling-chamber, there being a passage in the lower portion of the steamer affording communication between said chambers, a filling-opening to

said filling-chamber in the top wall of said casing, and a steam-outlet from said steam-chamber.

2. A steamer comprising a casing having a top wall and being arranged to have heat applied to the bottom thereof, and a partition dividing the interior of said casing into a filling-chamber and a steam-chamber and extending in downwardly-inclined disposition from the top wall of said casing toward the bottom and under said filling-chamber and having its lower edge disposed above the bottom of said casing whereby there is provided a passage affording communication between said chambers, there being a filling-opening to said filling-chamber in the top wall of said casing and a steam-outlet from said steam-chamber.

3. A steamer having a top wall, and a bottom arranged to have heat applied thereto, said casing containing a partition dividing the interior into a filling-chamber and a steam-chamber, there being a passage in the lower portion of the steamer affording communication between said chambers, a steam-outlet from said steam-chamber, and a filling-opening to said filling-chamber in the top wall, and a depending inwardly-inclined flange on the under side of said top wall surrounding said filling-opening.

4. In a steamer, the combination, with a casing having a bottom arranged to have heat applied thereto and a top wall, of a partition dividing the interior of the casing into a filling-chamber and a steam-chamber and extending in downwardly-inclined disposition from the top wall toward the bottom and under said filling-chamber, there being a passage in the lower portion of the casing affording communication between said chambers, a steam-outlet from said steam-chamber, and a filling opening to said filling-chamber in the top wall, and a depending inwardly-inclined flange on the under side of said top wall surrounding said filling-opening.

In testimony whereof I affix my signature.

LEROY SAXON WORSLEY.
